ATTORNEY

UNITED STATES PATENT OFFICE

JOSEPH SUNNEN, OF KIRKWOOD, MISSOURI

PORTABLE SUPPORT FOR EXHAUST DEVICES

Application filed January 15, 1931. Serial No. 508,914.

This invention relates to new and useful improvements in portable supports for exhaust devices, and particularly for vacuum cleaners and exhaust devices used in connection with automobiles.

The objects of the invention are to provide a simple support to which the vacuum or suction device is attached and which is so constructed that it may be readily suspended 10 from the door of an automobile or the back of the seat thereof or from any other suitable part of the automobile.

Additional objects of the invention are to provide a portable support adapted to have 15 detachably secured thereto a suitable suction device, said support being of simple but rugged construction, light in weight so as not to increase the weight of the suction device with which it is associated, and being so constructed that it can be economically manufactured.

With these and other objects in view, my invention consists in certain novel features of construction and arrangement of parts, 25 hereinafter more fully described and claimed, and illustrated in the accompanying drawing, in which—

Figure 1 is a top plan view of my portable support showing the suction device attached 30 thereto.

Figure 2 is a front elevational view of my portable support.

Figure 3 is an end elevational view of same showing it supported by the door which 35 is shown in dotted lines.

Figure 4 is an enlarged horizontal cross section taken on line 4—4 of Figure 2.

My improved portable support is especially designed to support a suction device which 40 is used in connection with my grit remover, the latter being disclosed in my copending application filed April 11, 1930, Serial No. 443,293, but said suction device can also be used as a vacuum cleaner for cleaning upholstery and the interior of automobiles.

Referring by numerals to the accompanying drawing, 10 indicates a pair of vertically disposed spaced members which are connected by a horizontally disposed member 11. 45 Members 10 are comparatively narrow and

can be made from stock material of commercial width and thickness. Horizontally disposed member 11 is comparatively wide and the ends thereof are secured to the intermediate portion 12 of each member 10 in any 55 suitable manner, such as rivets 14.

The upper end portion 15 of each member 10 is curved rearwardly and downwardly and the extremity of each of said portions is formed with a small reverse curve as indicated at 16. The lower end portion of each member 10 is curved inwardly as indicated at 17 with the extremity 18 presented outwardly and substantially in the same vertical plane with the intermediate portion 12. 60

The radius of each upper curved portion 15 is comparatively large in order to permit said portions to be hooked over the upper edge of an automobile door A or over the back of the seat or other suitable part of the automobile. The radius of the lower curved portion 17 is comparatively small, the purpose being to present the convex portion against the adjacent side of the door or the like and to bring the end 18 away therefrom. 70

As a further precaution against marring the surface of the door and protecting the upholstery of the automobile against injury the upper end portions 15 are covered by rubber tubing 19 and the lower end portions 75 17 are covered by rubber tubing 20.

Intermediate portion 12 is provided with apertures 21 for receiving anchoring means 22 of an exhaust device B, as shown in Figure 1. This device, which usually consists of 80 a blower and electric motor, is provided at its discharge end with a receiver bag C while the intake end of the device is connected to a flexible tubular connection D. The other end of this connection (not shown) is connected either to the grit remover or to a suitable nozzle when used for cleaning purposes.

A handle 24 is secured to intermediate portion 12 as indicated at 25 and extends upwardly therefrom. This handle is preferably of inverted U-shape, the ends of the leg portions being secured to said intermediate portion and said leg portions being offset laterally as indicated at 26 so as to space said 100

handle laterally from said intermediate portion and bring it in proper relation with the suction device and insure proper balancing when carried by hand.

5 The rubber covered upper portions 15 permit ready suspension of the support from any suitable rigid part and the convex faces of lower portions 17 contact with the adjacent surface and serve to impart stability to the

10 support.

The exhaust or vacuum device and parts associated therewith extend outwardly from plate or member 12 and are held in spaced relation with said adjacent surface and

15 therefore cannot injure the same.

I claim.

A portable support for suction apparatus for automobile grit removers and vacuum cleaners comprising in combination a pair of 20 vertically disposed spaced members, the upper end portion of each of which is curved rearwardly and downwardly to form a hook by means of which said support can be suspended from an automobile door and the like, 25 the lower end of each of said members being slightly curved to present a convex surface to the outer face of said door and hold said support in spaced relation therewith, a horizontally disposed apertured plate secured at 30 its ends to said vertical members intermediate the ends thereof, a suction apparatus, bolts engaging said apertured plate for securing said apparatus to said horizontal plate, said suction apparatus extending outwardly therefrom in a direction opposite to the curved upper end portions of said vertical members, and a handle attached to said horizontal member and extending upwardly and laterally therefrom to effect proper balancing 35 of the combined weight of said suction apparatus and said support when carried by hand.

In testimony whereof I hereunto affix my signature this 26th day of December, 1930.

45

JOSEPH SUNNEN.
